UNITED STATES PATENT OFFICE.

WILLIAM J. DOEPKER, OF AKRON, OHIO.

LAMP.

1,311,681.

Specification of Letters Patent.

Patented July 29, 1919.

Application filed June 13, 1918. Serial No. 239,744.

To all whom it may concern:

Be it known that I, WILLIAM J. DOEPKER, a citizen of the United States, residing at Akron, in the county of Summit and State 5 of Ohio, have invented new and useful Improvements in Lamps, of which the following is a specification.

This invention relates to a lamp especially designed for use on vehicles.
10 The object of the invention is to provide a lamp for lighting the roadway in advance of a vehicle and so constructed that the rays of light will not blind the driver of an approaching vehicle and will at the same time sufficiently illuminate the roadway in front of the vehicle carrying the lamp. A further object of the invention is to provide a lamp with a window opening usually provided with a translucent pane of 15 colored glass to constitute a warning signal.

With the foregoing and other objects in view, the invention consists in the novel construction, combination and arrangement of parts constituting the invention to be 20 hereinafter specifically described and illustrated in the accompanying drawings which form a part hereof wherein is shown the preferred embodiment of the invention, but it is to be understood that changes, variations and modifications can be resorted to which come within the scope of the matter 25 hereinafter claimed.

In the drawings in which similar reference numerals indicate like parts in the different figures,

Figure 1 is a side elevation of a lamp embodying the present invention.

Fig. 2 is a plan view of the device shown in Fig. 1 with a portion broken away.

40 Fig. 3 is an end elevation looking from the right in Figs. 1 and 2.

Fig. 4 is an enlarged view in perspective of a position of the open end of the lamp body, and

45 Fig. 5 is a longitudinal sectional view of that portion of the lamp which contains the signal opening.

The device comprises a conoidally or parabolically-shaped body member 1 having 50 an open end and provided with a hollow supporting standard 2 the interior of which is in open communication with the interior of the body member 1. The front of the flaring open end of the body member 1 is 55 provided with an approximately semi-circular retaining flange 3 which is U-shaped in

cross section and constitutes one member of a coupling element for uniting the body member to other mechanism to be later described. Disposed within the body member 60 1 is a reflector 4 the general shape of which approximates the shape of the body member 1 and the front open edge of this reflector is turned back or curled at 5 to constitute a form of beading for engagement with the 65 inner face of the member 1 near the flange 3. At the inner end of the reflector 4 is a socket 6 for an electric lamp 7 to which current is supplied by means of wires contained in a cable 8 extending through the hollow 70 support 2. The body member is so arranged with respect to the hollow support 2 that the axis of the member is inclined downwardly at an angle approximating 30° thereby throwing the rays of light from the lamp 7 75 onto the roadway immediately in advance of the vehicle on which the lamp is mounted. Arranged to coöperate with the body member 1 is a deflector 8' the rear portion of which is oval in transverse cross section in 80 order to adjust itself for engagement and connection with the open front end of the body member 1 and also is provided adjacent to the open end with a beading 9 suitably fashioned to be received in the U- 85 shaped flange 3 on the body member 1. The beading 9 is spaced from the edge of the open end of the member 8' to provide a flange 10 which incloses the member 1, and the portions of the flange 10 which are adjacent to the U-shaped flange 3 when the parts are positioned are fastened onto straps 11 which are freely movable with respect to 90 the member 8' and are arranged to inclose the open end of the body member 1. These 95 straps are provided with ears 12 as clearly shown in Figs. 1 and 3 and extending through these ears is a clamping bolt 13 which when properly manipulated clamps the straps about the open end of the member 100 1 for temporarily uniting or coupling the members 1 and 8' together. The front portion 14 of the member 8' is widely flaring and is equipped with a forwardly-extending downwardly-projecting shield 15. Rearwardly of the shield 15 the under face of the member 8' is open to permit the rays of light from the lamp 7 to project forwardly and downwardly. Preferably formed integrally with the upper face of the member 105 8' is a hollow projection 16 in the general form of a dormer window with an open

front end 17. The edges of the material forming the upper and side walls of the projection 16 are indent at 18 to form a portion of a casing and the lower wall at 19 is 5 U-shaped to constitute a seat for a sheet of translucent material 20 which usually consists of a pane of colored glass. On the under face of the upper wall of the projection 16 is a stop 21, arranged to engage the 10 glass 20 for holding it in place and against movement.

The device is mounted by any suitable means on a vehicle using the support 2 for this purpose and the rays of light from the 15 lamp 7 are projected forward through the member 8' downwardly onto the roadway in advance of a vehicle but are not projected in a straight line to embarrass or blind either pedestrians or the drivers of approaching 20 vehicles while at the same time furnishing sufficient illumination for the use of the driver of the vehicle on which the device is mounted. At the same time and to serve as a warning the rays of light from the lamp 25 are projected through the pane of colored glass 20 to constitute a warning signal to the driver of an approaching vehicle.

I claim,
A device of the class described compris-

ing a body member approximately para- 30 bolically-shaped in longitudinal cross section, a reflector positioned in said body member, a lamp positioned at the focal center of said reflector, said body member provided with a U-shaped coupling flange ex- 35 tends partially around the marginal edge of the open end thereof, a light deflector comprising a hollow fan-shaped structure having an open end the marginal portion of which is fashioned to interlock with the 40 flange on said body member for coupling said deflector and body member together, the upper wall of said deflector being inclined downwardly at an angle approximating 30°, said upper wall provided with 45 a hollow projection in the general form of a dormer window, the front open end thereof provided with a pane of translucent material, the lower portion of said deflector being open to permit the rays of light from 50 said lamp to project abruptly downwardly and forwardly within well defined lines and immediately in advance of the entire structure.

In testimony whereof I have hereunto set 55 my hand.

WILLIAM J. DOEPKER.
